UNITED STATES PATENT OFFICE.

JOHN H. BECKER, OF HAZLETON, PENNSYLVANIA, ASSIGNOR TO ANTHRACITE
SEPARATOR COMPANY, A CORPORATION OF PENNSYLVANIA.

ADJUSTABLE SPIRAL SEPARATOR.

Application filed October 7, 1921. Serial No. 506,115.

To all whom it may concern:

Be it known that I, JOHN H. BECKER, a citizen of the United States, and resident of Hazleton, Pennsylvania, have invented 5 certain new and useful Improvements in Adjustable Spiral Separators, of which the following is a specification.

This invention relates to means for separating different grades of material according 10 to the frictional resistance exerted on a spiral runway and the differential centrifugal action of the varying classes of material traveling on the runway. The separator is particularly adapted for separating the refuse 15 or impure coal and slate from the pure or high grade coal, but is not limited to such use as it could readily be used for separating various other materials having different frictional characteristics.

20 One object of the invention is to provide a spiral separator constructed so that the diameter thereof can be varied to permit part of the material being handled to "skim" or fly off the spiral runway at 25 different radial distances from the axis of the separator. Another object is to provide simple and inexpensive means for varying the width of the runway. A further object is to provide means for simultaneously adjusting the width of the runway at several 30 locations on the separator. A still further object is to combine and co-ordinate the several component elements of the structure described so as to perform the functions set forth. Other objects will be apparent from the following specification when read in connection with the accompanying drawings in which—

Fig. 1 is a side elevation of a separator 40 embodying my invention, parts being broken away in the interest of clearness;

Fig. 2 is a horizontal section on an enlarged scale;

Fig. 3 is a detail of a fixed segment having an adjustable portion secured thereto;

Fig. 4 is a section on the line 4—4 of Fig. 2.

50 Referring to the embodiment illustrated, the central supporting post 1 carries a plurality of inclined radially extending rods 2 which are adapted to support the fixed segments 3 and 4 forming the spiral runway. The separator may be built with any desired number of separating threads or runways 5, 55 the one illustrated in Fig. 1 having three

such runways. An outer conveyor thread 6, of considerably larger diameter than the runway 5, is supported on rods 7 carried by the central post 1. This thread is formed with an upright flange 6^a and is arranged to receive the pure coal which is skimmed or thrown off of the separator runways 5 by centrifugal force as it travels on its downward course. The separator threads are each provided at the top with a flange 6^b 60 which extends about half way around the outer periphery. Inclined chutes 8 are connected in any suitable manner to the upper ends of the runway 5 and are preferably adjustably supported by a suitable hanger 9. 70

Each runway 5 is provided with movable portions whereby the width or supporting area thereof may be varied to conform to the inherent frictional characteristics of the material being handled. In the embodiment 75 illustrated the fixed segments 4 are shaped so that the radial length of the side 10 is much shorter than the side 11 and the outer edge 12 is either straight as shown or curved on an arc eccentric to the axis of the separator. Swinging members 13 are pivoted at 14 to the segments 4 and their outer edges 15 are curved to conform approximately to the arc of a circle struck from the axis of the supporting post, when they are 80 swung to the extreme outward position. The members 13 are connected by means of short links 16 to a spiral bar 17 which is 85 slidably mounted in suitable brackets on the under side of the fixed segments of the runway. The bar 17 is actuated by a hand lever 18 pivoted at 19 and connected by a short link 20 to said bar. All of the members 13 in each runway 5 may be connected to a single spiral bar 17 so they will all be 90 moved simultaneously, or there may be a plurality of spiral bars each actuated by a suitable lever 18 so as to permit of independent adjustment of the width of different parts of the separator runways.

100 In treating some classes of material it is advantageous to individually adjust the position of the swinging members. This can be done by disconnecting the links 16 and inserting a bolt through one of the several holes 21 in the member 13 and screwing it into a tapped hole in the adjacent supporting rod.

105 The separator may be built up of plain segments 3 and segments 4 having adjust- 110

able members 5 alternately arranged as shown in the upper part of Fig. 2, or adjacent segments may be adjustable as shown in the lower part of the figure. The floor 5 of the runway may be provided with suitable friction plates or jackets or may be formed with ribs 22 as shown in Figs. 3 and 4.

In operation the mixed material to be separated is fed to the inclined chutes 8 which deliver it to the separator threads or spiral runways 5. The mass in traveling along the runway separates into different streams according to the frictional characteristics thereof. In handling coal and slate mixtures, the coal being brighter or smoother travels in an outer path and at a higher speed while the slate, bony coal and other impurities travel along an inner path. The purer coal is thrown outwardly by centrifugal force and caught by the conveyor thread 6 which carries it to a suitable chute or bin not shown. The coal traveling the outer path and slate or refuse traveling on the inner path of the runway is deflected, at the bottom of the runway, by suitable ridge plates of known construction to separate chutes leading to storage bins.

By adjusting the position of the movable members it will be apparent that the separator can be regulated to vary the width or the effective supporting area of the runway to release the purer coal to the coal thread. Thus a given separator can be used for materials having widely different inherent frictional characteristics. The adjustable members permit the use of a single separator for handling either wet or dry materials, or coal from different veins, and coals of different fractures. Materials such as coal and slate from different veins vary as to the percentage of good coal and refuse and travel in wider or narrower paths or "lines of friction" on the floor of the runway.

By varying the width of the runway as

above described, the operator can readily set the separator so as to effectively separate the different classes of materials handled.

While I have described with great particularity the embodiment of the invention herein illustrated it is not to be construed that I am limited thereto as changes in arrangement and substitution of equivalents may be made without departing from the invention as defined in the following claims.

What I claim is:

1. A separator having a spiral runway over which the material to be separated travels, pivoted plates secured at different points along the runway and forming part of the supporting area thereof and means for simultaneously moving the several plates inwardly and outwardly.

2. A separator having a spiral runway comprising a plurality of fixed segmental plates, an adjustable plate pivoted at one end to a point adjacent the periphery of the runway and means co-operating with the opposite end of the plate or locking the latter in different adjusted positions.

3. A separator having a spiral runway, swinging plates pivotally secured at the periphery of the runway, a spiral bar supported in juxtaposition to said runway and operatively connected to said swinging plates so as to move several of them simultaneously.

4. A spiral separator comprising a central supporting post, a series of inwardly and downwardly inclined segmental plates supported by said post, certain of said plates having portions of less radial length than adjacent plates with which they are associated so as to form an interrupted outer contour and swinging members mounted adjacent to the interrupted portions of the runway and arranged to vary the supporting area of said runway.

In witness whereof, I have hereunto signed my name.

JOHN H. BECKER.
